BOTTLE

John J. Anderson, Kenosha, Wis., assignor to S. C.
Johnson & Son, Inc., Racine, Wis.

Filed Dec. 11, 1967, Ser. No. 9,715

Term of patent 14 years

(Cl. D9—97)

Fig. 1.

Fig. 3.

Fig. 2.

FIG. 1 is a top view of a bottle embodying my new design;

FIG. 2 is a side elevational view thereof; and

FIG. 3 is a perspective view thereof.

The dominant features of my design reside in the portions shown in full lines.

I claim:

The ornamental design for a bottle, as shown and described.
